AUTOMOBILE WHEEL COVER

Eugene Bordinat, Jr., Bloomfield Hills, Mich., assignor to Ford Motor Company, Dearborn, Mich., a corporation of Delaware

Filed Dec. 18, 1961, Ser. No. 67,944

Term of patent 7 years

(Cl. D14—30)

FIG. 1

FIG. 2

FIG. 3

I claim:

The ornamental design for an automobile wheel cover, substantially as shown.
